ABSTRACT OF THE DISCLOSURE

Addition of ethers as promoters for Lewis acid catalyzed isomerization, preferably taking place within a halo-aromatic solvent, results in the suppression of cracking and a corresponding maximization of the desired isomerization products. The ethers contain at least one secondary or tertiary alkyl radicals or cycloalkyl radicals.

PRIOR ART

This invention relates to the use of promoters in the Lewis acid catalyzed isomerization of paraffins. More particularly, the invention relates to improvements in the liquid phase conversion of normal or branched chain hydrocarbons to the more desirable highly branched isomers. This conversion is, according to the instant invention, greatly improved by the addition of an ether to said Lewis acid system, said ether containing at least one secondary or tertiary grouping.

In the past, a great deal of effort has been expended in various attempts to improve the isomerization reaction. Basically, it has been recognized that cracking is an undesirable side reaction associated with high catalyst consumption and must be minimized. Thus, cracking must be inhibited both to suppress the formation of unwanted hydrocarbon products and to extend the useful life of the catalyst.

The prior art contains many different techniques for inhibiting cracking in the isomerization reaction.

Generally, these techniques involve the use of naphthenes, aromatics and hydrogen as cracking suppressors; but little attention has been paid to the role of initiating reagents in influencing the selectivity of the isomerization reaction. The suppressors are used in conjunction with the traditional promoters which are required to initiate the isomerization of paraffins over Lewis acids; such promoters include trace amounts of olefins and hydrogen halides, as well as alkyl halides, water and oxygen. An extended discussion of the suppressors and promoters is to be found in H. Pines and J. M. Marity "The Chemistry of Petroleum Hydrocarbons" Chapter 39, Brooks, Kurtz, Boord & Schmerling, Reinhold Publication, vol. #8, 1955. The disclosure of which is herein incorporated by reference.

More recently, in U.S. Pat. 2,956,097 the use of a perhalogenated carbonaceous compound in which one of the halogen atoms is fluorine is recommended for use as a promoter in the isomerization reaction at critical temperatures. This type of promoter and others which have been utilized contemporaneously with it have met with limited success in facilitating the economical isomerization of paraffins since, although, they successfully promote the reaction they do not simultaneously suppress the undesired cracking.

SUMMARY OF THIS INVENTION

According to this invention, it has unexpectedly been discovered that the addition of particular ethers as promoters for a Lewis acid catalyzed isomerization, preferably taking place within a halo-aromatic solvent, results

2

in the suppression of cracking within the isomerization reaction and a corresponding maximization of the desired isomerization products. The ethers may be employed with or without conventional cracking inhibitors. The particular ethers to be utilized are those having at least one secondary or tertiary alkyl, secondary cycloalkyl or tertiary cycloalkyl grouping. The ethers will have the formula R_1-O-R_2 wherein R_1 is selected from the group consisting of C_3 to C_7 , secondary and tertiary alkyl radicals. R_1 may also be a secondary cycloalkyl or tertiary cycloalkyl ligand having 3 to 7 carbons. R_1 is preferably a C_3 to C_5 secondary or tertiary alkyl radical and most preferably a C_4 to C_6 tertiary alkyl radical.

R_2 may be either a primary C_1 to C_7 alkyl radical or a secondary or tertiary C_3 to C_7 alkyl radical. C_3 to C_7 secondary or tertiary cycloalkyls may also be utilized; i.e., alkylcyclopropyl through alkylcycloheptyl ligands.

The promoter is used in conjunction with a Lewis acid. In brief, a Lewis acid is any molecule, radical or ion in which the normal electron grouping about a given atom is incomplete so that the atom may accept an electron pair or pairs. The promoter comprises a minor proportion of the catalyst and the Lewis acid comprises the major proportion of the catalyst excluding the support. Such a catalyst is contacted at reaction conditions with a paraffinic feed stream, preferably a C_4 through C_7 containing naphtha feed stream in which there is a substantial proportion of normal paraffinic hydrocarbons. The normal paraffinic hydrocarbons are isomerized and are converted to the desired state in which they possess higher octane.

Contacting of catalyst, promoter and feed stream is for extended periods of up to about 24 hours; temperatures are elevated and may range broadly from 30 to 300° F. Pressures may also be elevated and should range between 15 and 150 p.s.i.g.

It is most preferred that the contacting take place within a solvent, the solvent is preferably a halo-aromatic solvent such as 1,2,3-trichlorobenzene, 1,2,4-trichlorobenzene, 1,2,4,5-tetrachlorobenzene, or pentachlorobenzene, and the corresponding bromo and fluoroaromatics. The highly substituted chloro and bromoaromatics including the hexahalo derivatives may also be used as solid supports by operating below the freezing point of the respective compounds. Following the contacting between the catalyst, promoter and feed stream, a product is recovered which is enriched in isomerized paraffins, at the same time, cracking of the feed stream is minimized and the ratio of isomerized products recovered to cracked products is improved. Comparing the promotional effect of methyl-t-amyl ether with t-amyl chloride (a well known and typical promoter) it is seen that the isomerization/cracking ratio obtained with the ether is about (3-5)/1 whereas with the alkyl halide it is about (0.5-1.5)/1. The substantial increase in selectivity makes the ether the promoter of choice.

In more detail, the process of the instant invention relates to a method for isomerizing normal and isoparaffins and aliphatic naphthas, and in particular normal paraffins, isoparaffins and naphthas of C_4 to C_7 chain length. Typical isomerization reactions which would take place according to the process of the instant invention include the conversion of normal pentane to isopentane, normal butane to isobutane, normal hexane and a C_6 naphtha to the equilibrium distribution of hexanes containing large amounts of 2,2-dimethylbutane and 2,3-dimethylbutane, and n-heptane and C_7 naphthas to the highly branched isomers 2,2,3-trimethylbutane, 2,2-dimethylpentane, 3,3-dimethylpentane, 2,3-dimethylpentane and 2,4-dimethylpentane. The catalyst will also catalyze the isomerization of methylcyclopentane to cyclo-

hexane which is valuable as a chemical intermediate, and the general isomerization of alkyl cycloalkanes to the equilibrium distribution of isomers.

Typical feed streams which would include normal paraffins in the C₄ to C₇ range are naphthas both virgin and cracked boiling between 10 and 210° F. The butane stream obtained at the tail end of the butane-olefin alkylation process and the paraffins remaining after extracting light olefins from cat cracked streams are also typical feeds for the process.

The above-mentioned feed streams are contacted, preferably in the liquid phase, with the combination of catalyst and promoter of the instant invention. Typical Lewis acids which may be effectively used for isomerization include aluminum chloride, boron trifluoride, antimony pentafluoride and aluminum bromide.

The other element of the catalyst or promoter, has the general configuration R₁—O—R₂. R₂ may be a C₁ to C₇ primary or C₃ to C₇ secondary or C₄ to C₇ tertiary alkyl group, and is preferably a methyl or ethyl group. Typical ligands which may be used for R₂ include the following: methyl, ethyl, n-propyl and sec-propyl, isobutyl, sec-butyl and t-butyl, cyclopentyl etc. Cycloalkyls are included within the above categories. R₁ differs from R₂ in that R₁ is restricted to secondary and tertiary alkyls or cycloalkyls. Most preferred ligands for R₁ are the tertiary alkyls especially the t-butyl and t-amyl groups. The combination of catalyst and promoter is present in the proportion of about 90 to 99.9 mol. percent of catalyst to about 0.1 to 10 mol. percent of the promoter. Preferably about 95 to 99.5 mol. percent catalyst is utilized to about 0.5 to 5 mol. percent of the promoter.

The isomerization itself takes place preferably within a solvent although by using the haloaromatics below the melting point of the system a supported catalyst may be employed. A haloaromatic solvent is preferred and most preferably the solvent would be 1,2,3-trichlorobenzene, 1,2,4 - trichlorobenzene, 1,2,4,5 - tetrachlorobenzene, the corresponding fluorobenzenes and pentafluoro and hexa-fluorobenzene, and 1,2,3-tribromobenzene and 1,2,4-tri-bromobenzene. Other halo aromatics include halogenated C₆ through C₂₀ aromatics including those which have condensed rings such as naphthalene. In general, liquid aromatics whose basicity has been severely lowered by reason of the inclusion of a number of halogen atoms in their skeleton are acceptable solvents for the isomerization process.

Temperatures may vary widely; a broad range of about 30 to 300° F. may be used, preferably 70 to 200° F. Pressures may vary widely too but a range of 15 to 150 p.s.i.g. is acceptable. The preferred range for pressure would be between 15 p.s.i.g. and 100 p.s.i.g.

The contacting may take place in a batch or continuous operation. It is preferred to use a continuous operation in which flow rates of about 0.1 to about 5 v./v./hr. may be used. For a batch operation the following apparatus would be needed. A reactor made out of steel or monel, preferably containing inert walls; glass, porcelain or Teflon-lined although these are not required, and fitted with provisions for stirring, adding and withdrawing reagents is used for the isomerization. The products are separated from the catalyst by standard means such as by distillation. In a continuous operation, the apparatus would contain sections for the continuous introduction of feed to the reactor and for the continuous withdrawal of the catalyst-solvent-hydrocarbon system to a separator. Product would be collected at the separator and the catalyst and solvent would be recycled to the reactor. Provisions would be required for the continuous introduction of small amounts of the catalyst and promoter to replace that which is consumed during the operation.

Aromatics and other basic materials that tend to be detrimental to the isomerization reaction may be substantially removed from the feed by conventional means,

such as with molecular sieves, or by acid treating, solvent extraction, mild hydrogenation or the like.

Although not intending to be bound by any specific theory as to operation, the following is offered to explain the favorable results of the instant invention, i.e., the minimization of cracking and maximization of isomerization.

Utilization of methyl-t-amyl ether as a promoter typical of this invention is believed to lead to the formation of Complex I which is in equilibrium

with a tight ion pair, II. The t-amyl cation is believed to be relatively closely associated with the ether oxygen thus restricting its reaction possibilities. During the isomerization of a paraffin-like n-hexane, the t-amyl ion abstracts a hydride ion from n-hexane forming isopen-tane and a sec-hexyl ion. This is a necessary reaction for any isomerization catalyst.

The detrimental reaction which is impeded is one by which the t-amyl cation reacts with a bromine atom of the R₁Br₆ molecule with which it is associated to form HBr and an olefin. If aluminum bromide is promoted with a conventional t-alkyl halide, the initial complex resembles III,

50 which is believed to ionize to yield an anion in which the charge is spread out over the bulk of the anion, (in contrast to the localized charge obtained with the ether). The cation is therefore less intimately bound to a given site of the anion and more readily reacts to form HBr and an olefin. Evidence that this model is valid may be obtained by measuring the pressure generated upon the addition of these promoters to the AlBr₃-1,2,4 Cl₃C₆H₃ system. From the above it is apparent that in order to initiate the reaction at least one secondary or tertiary alkyl grouping must be present in the ether, i.e. as in methyl-t-amyl ether.

SPECIFIC EMBODIMENTS

EXAMPLE 1

55 In this example comparisons were made between t-amylchloride, t-amylalcohol and t-amylmethyl ether to determine their effect on the isomerization of normal hexane. A solution of 0.25 ml. n-hexane and 0.5 ml. 1,2,4-trichlorobenzene was contacted with each of the three catalyst-promoter systems under identical conditions. Temperature for all runs was 77° F., pressures were ambient and contacting times were 15 minutes. The homogeneous solution was allowed to stand for this time and products were recovered by vacuum distillation at room temperature.

TABLE I

Promoter, M ^a	Reactant n-Hexane		
	t-Amyl-chloride, .02 M	t-Amyl-alcohol, .02 M	t-Amyl-methyl ether, .02 M
AlBr ₃ , M ^a	0.5	0.5	0.5
Conv., percent	b 15.5	3.8	5.3
Isom./cracking	b 1.6/1	1.6/1	4.6/1

^a These are the promoter and AlBr₃ concentrations in 1,2,4-trichlorobenzenes.

^b The low isom/cracking ratio is characteristic of t-Amylchloride promotion, apparently independent of conversion. Other data at 8 and 48% conversion with .05 M AlBr₃ and .04 M t-Amylchloride show I/C ratios of 1.2 and 0.7.

The percent conversion was determined by a chromatographic analysis of the recovered products and the ratio of isomerization to cracking was determined by dividing the weight percent of C₆ isomers by the combined weight percent of all lighter and heavier components. A terse study of the table indicates that when making use of t-amylmethyl ether a ratio of isomerization to cracking which is three times as high was achieved. This indicates clearly a superior suppression of the cracking reaction.

EXAMPLE 2

In Table II the behavior of t-amyl chloride and methyl-t-amyl ether are compared over another catalyst at 149° F. Again 0.25 ml. of n-hexane was contacted with 0.5 ml. of 1,2,4-trichlorobenzene containing 0.5 M AlBr₃. The promoter concentrations and reaction times were varied to permit an evaluation of the isomerization/cracking ratio as a function of reaction rate and conversion.

TABLE II

Selectivity Rate Relationships for n-Hexane Isomerization in 0.5 M AlBr₃-1,2,4-Cl₃C₆H₅, 149° F.

Promoter	M	Time, min.	K, hr. ^a	Isom./crack.	Conversion
t-C ₆ H ₁₁ Cl	0.02	15	0.43	0.55	10.1
t-C ₆ H ₁₁ Cl	0.002	15	0.03	0.59	0.9
t-C ₆ H ₁₁ OCH ₃	0.001	120	0.02	4.85	4.0
t-C ₆ H ₁₁ OCH ₃	0.005	60	0.03	3.23	3.0
t-C ₆ H ₁₁ OCH ₃	0.01	15	0.06	3.6	1.6
t-C ₆ H ₁₁ OCH ₃	0.02	15	0.13	3.9	3.3

^a Apparent first order rate constant for hexane conversion to all products.

Examination of Table II shows the isomerization/cracking ratio to be 7-8 times as selective with ether promotion than with t-amyl chloride. The improved selectivity is independent at isomerization rate or the extent of conversion. Further the isomerization/cracking ratio is shown to be a characteristic of the type of promoter since t-amyl-chloride gives the same product distribution over a 10-fold change in concentration and methyl-t-amyl ether gives its characteristic products over a 20-fold change in concentration.

The product analysis was made as in Example 1.

EXAMPLE 3

In this example the same conditions and reactants as in Example 1 are utilized except that methyl-t-butyl ether is substituted for t-amyl methyl ether, substantially identical results are observed.

Methyl-t-amyl ether is a readily available compound that can be made by condensing 2-methyl-1-butene or 2-methyl-2-butene with methanol in the presence of a small amount of sulfuric acid.

What is claimed is:

1. A process for isomerizing paraffinic hydrocarbons into more highly branched chain paraffinic hydrocarbons which comprises contacting said hydrocarbons in the liquid phase, at reaction conditions with a Lewis acid catalyst and a promoter, said promoter being an ether having the formula R₁-O-R₂ wherein R₁ is selected from the group consisting of secondary, tertiary alkyl radicals and secondary, tertiary cycloalkyl radicals and R₂ is selected from the group consisting of primary, secondary and tertiary alkyl radicals and secondary and tertiary cycloalkyls and wherein the amounts of said catalyst and said promoter present are in the proportion ranging from about 90-99.9 mole percent of catalyst to about 0.1-10 mole percent of the promoter.
2. The process of claim 1 wherein said paraffinic hydrocarbons are in a naphtha feed stream.
3. The process of claim 1 wherein said catalyst and said promoter are dissolved in a halogenated aromatic solvent.
4. The process of claim 1 wherein said paraffinic hydrocarbons are C₄ to C₇ paraffins.
5. The process of claim 1 wherein said catalyst is selected from the group consisting of aluminum chloride and aluminum bromide.
6. The process of claim 1 wherein the solvent is a trichlorobenzene.
7. A process for isomerizing a C₄ through C₇ paraffinic feed stream into more highly branched paraffins which comprises contacting said feed stream, in the liquid phase, at reaction conditions, with a major portion of a Lewis acid catalyst and a minor portion of a promoter, said promoter having the general configuration R₁-O-R₂ wherein R₁ is selected from the group consisting of C₃ to C₇ secondary, C₄ to C₇ tertiary and C₃ to C₇ cycloalkyl radicals and R₂ is selected from the group consisting of C₁ to C₇ primary, C₃ to C₇ secondary, C₄ to C₇ tertiary and cycloalkyl radicals containing C₃ through C₇ rings, wherein said major portion of catalyst ranges from about 95-99.5 mole percent and the amount of said promoter ranges from about 0.5-5 mole percent and recovering an isomerized product.
8. The process of claim 7 wherein said contacting takes place within an organic solvent.
9. The process of claim 8 wherein said catalyst is selected from the group consisting of aluminum chloride and aluminum bromide.
10. The process of claim 8 wherein said solvent is a trichloro aromatic solvent.
11. The process of claim 8 wherein said ether is methyl-t-amyl ether.
12. The process of claim 8 wherein said contacting takes place at a temperature of 30 to 300° F.
